END PLATE FOR BICYCLE PEDAL

Harry Golden, Brooklyn, N. Y.

Application March 7, 1955, Serial No. 34,912

Term of patent 7 years

(Cl. D90—14)

Fig. 1.

Fig. 2.

Fig. 3.

Figure 1 is a front elevation of an end plate for bicycle pedals embodying my new design;

Figure 2 is a top plan view thereof; and

Figure 3 is a front end elevation of the same.

My design resides in the showing illustrated in full lines in the drawing. The fragmentary dotted line disclosure of other pedal elements are disclosed only for the purpose of illustration.

I claim:

The ornamental design for an end plate for bicycle pedal, as shown and described.
